(57) **CLAIM**

The ornamental design for a gun lock, substantially as shown and described.

DESCRIPTION

FIG. 1 is a front, bottom perspective view of a gun lock showing our new design.

FIG. 2 is a front, top perspective view thereof.

FIG. 3 is a front, bottom perspective view of the parts of the gun lock separated.

FIG. 4 is a front, top perspective view thereof.

FIG. 5 is a front view of the gun lock of FIG. 1.

FIG. 6 is a rear view thereof.

FIG. 7 is a top view of the gun lock of FIG. 1 with the switch in a first position.

FIG. 8 is a front, bottom perspective view of the male part of the gun lock of FIG. 1 with the switch having been placed in the first position.

FIG. 9 is a top view of the gun lock of FIG. 1 with the switch in a second position.

FIG. 10 is a front, bottom perspective view of the male part of the gun lock of FIG. 1 with the switch having been placed in the second position.

FIG. 11 is a bottom view of the male part of the gun lock of FIG. 1 with the switch having been placed in the first position.

FIG. 12 is a front view thereof.

FIG. 13 is a rear view thereof.

FIG. 14 is a right side view thereof.

FIG. 15 is a left side view thereof.

FIG. 16 is a top view of the female part of the gun lock of FIG. 1.

FIG. 17 is a bottom view thereof.

FIG. 18 is a front view thereof.

FIG. 19 is a rear view thereof.

FIG. 20 is a right side view thereof.

FIG. 21 is a left side view thereof.

FIG. 22 is a rear, top perspective view thereof; and,

FIG. 23 is a top view of the gun lock of FIG. 1 shown in a use configuration with environment.

(Continued)

The dashed lines depict portions of the gun lock that form no part of the claimed design. The dashed lines in FIG. 23 depicting the environment of a gun form no part of the claimed design. The surface shading and contour lines in the drawings do not illustrate surface ornamentations or surface decoration.

1 Claim, 6 Drawing Sheets
